(57) **CLAIM**

The ornamental design for a multimode cooker, as shown and described.

DESCRIPTION

FIG. 1 is a front perspective view of a slide knob mechanism for use with a multimode cooker;

FIG. 2 is a front view of the slide knob mechanism of FIG. 1;

FIG. 3 is a back view of the slide knob mechanism of FIG. 1;

FIG. 4 is a left view of the slide knob mechanism of FIG. 1;

FIG. 5 is a right view of the slide knob mechanism of FIG. 1;

FIG. 6 is a top view of the slide knob mechanism of FIG. 1; and,

FIG. 7 is a bottom view of the slide knob mechanism of FIG. 1.

The broken line shown in all of the drawing figures are for illustrative purposes only and form no part of the claimed design.

1 Claim, 7 Drawing Sheets
